Patented May 7, 1974

231,601

CONTAINER FOR LIQUIDS OR THE LIKE

Daniel S. Cvacho, Richmond, Va., assignor to Reynolds
Metals Company, Richmond, Va.

Filed Mar. 20, 1972, Ser. No. 236,548

Term of patent 14 years

Int. Cl. D9—03

U.S. Cl. D9—216

FIG. 5.FIG. 6.FIG. 7.FIG. 1 is a bottom perspective view of a container for liquids or the like embodying my new design;

FIG. 2 is an elevational view on an enlarged scale;

FIG. 3 is a bottom plan view on the same scale as FIG. 2;

FIG. 4 is an exploded, bottom perspective view on the same scale as FIG. 1;

FIG. 5 is a fragmentary view partially in section on a larger scale than FIG. 2;

FIG. 6 is a view similar to FIG. 5 showing a modified form of my new design; and

FIG. 7 is a view similar to FIG. 5 showing another modified form of my new design.

I claim:

The ornamental design for a container for liquids or the like, as shown and described.
